United States Patent Office

Des. 190,818
Patented July 4, 1961

190,818

TOY SPUR

Charles T. Norton, 12544 S. Ada St., Calumet Park, Ill.

Filed Sept. 20, 1960, Ser. No. 62,209

Term of patent 3½ years

(Cl. D34—15)

Fig. 1.

Fig. 2.

Fig. 3.

FIG. 1 is a side elevational view of a toy spur showing my new design;

FIG. 2 is a top plan view; and

FIG. 3 is an enlarged section on the line 3—3 of FIG. 2.

I claim:

The ornamental design for a toy spur, as shown.
